UNITED STATES PATENT OFFICE.

FRANK J. KROMENAKER AND GRANT M. KROMENAKER, OF CHICAGO, ILLINOIS.

INTERLOCKED SHINGLE.

Application filed February 24, 1923. Serial No. 620,950.

To all whom it may concern:

Be it known that we, FRANK J. KROMENAKER and GRANT M. KROMENAKER, both citizens of the United States, residing at Chicago, in the county of Cook and State of Illinois, have invented certain new and useful Improvements in Interlocked Shingles, of which the following is a specification.

The invention relates to interlocked shingles, and has for its object to provide a shingle which may be easily and quickly applied to a roof in such a manner that buckling or curling of the roofing material, from which the shingles are formed, will be obviated, and at the same time the shingle will present an artistic appearance, such as a substantially hexagon shape, having an upwardly extending portion.

A further object is to provide the slits of the shingles, where adjacent shingles interlock, with incisions extending away from the bottom of the slit, thereby insuring a tight joint without buckling.

A further object is to provide a shingle comprising an elongated member having its opposite sides provided with indentations and projections, the indentations and projections at each side of the shingle being in staggered relation to each other; further to provide transversely extending slits extending inwardly from the ends of the indentations at one side of the shingle in parallel relation with each other and terminating with oppositely extending slits.

With the above and other objects in view, the invention resides in the combination and arrangement of parts as hereinafter set forth, as shown in the drawings, and as described and claimed, it being understood that changes in the precise embodiment of the invention may be made within the scope of what is claimed without departing from the spirit of the invention.

In the drawing:

Figure 1 is a plan view of a section of roofing, formed from interengaged shingles; and

Fig. 2 is a perspective view of a portion of one of the shingles.

Referring to the drawing, the numeral 1 designates a shingle, and extending outwardly from the edge 2 thereof are angularly shaped extensions 3. Extending inwardly from the edge 2 and from the recesses 4 formed by the extension 3 are slits 5, which

are in parallel relation to each other, and which slits terminate adjacent the longitudinal center of the shingle, and also terminate in segmentally shaped slits 6, which curve away from each other and form means 60 for receiving the edges 7 of the adjacent shingle, as clearly shown in Figure 1. The edge 7 is provided with angularly shaped extensions 8, which extensions are in staggered relation to the extensions 3 and form 65 recesses 9 similar to the recesses 4, but in staggered relation to the recesses 4. The slits 5 form tongues 10, behind which tongues the edge 7 of the adjacent shingle is received and the tongues are then secured by means 70 of nails 11. It will be seen by reference to Figure 1 that a roof may be formed by superimposing and interengaging the shingles 1, and that a substantially hexagon shaped design is formed by the extensions 75 8 and a portion of the body of the shingle.

From the above it will be seen that an interlocked and interengaged shingle is provided which is simple in construction, and that the extensions 3 are positioned where 80 the nails 11 will pass therethrough thereby not only securing the tongues, but also adjacent shingles together. It will also be seen that by providing the curved slits 6, that buckling of the shingles will not take 85 place. The slits 6 are shown as semi-circular, however, it is to be understood that they may be L-shaped or of any other shape desired.

The invention having been set forth what is claimed as new and useful is:

1. A roofing shingle comprising an elongated member, spaced projections extending outwardly on opposite sides of the elongated member, the projections at each side of the 95 elongated member being in staggered relation to each other, thereby forming recesses at opposite sides of the member in staggered relation to each other, and slits extending inwardly from the ends of the recesses on one side of the member.

2. A roofing shingle comprising an elongated member, spaced projections extending outwardly on opposite sides of the elongated member, the projections at each side of the 105 elongated member being in staggered relation to each other, thereby forming recesses at opposite sides of the member in staggered relation to each other, and slits extending inwardly from the ends of the re- 110

cesses at one side of the member, the ends of the slits terminating in opposite extending short slits.

3. A roofing shingle comprising an elongated member, spaced projections at opposite sides of the elongated member and in staggered relation to each other, thereby forming spaced recesses in the opposite sides

of the member in staggered relation to each other, and slits extending inwardly from the ends of the recesses, said slits terminating in oppositely and outwardly extending slits.

FRANK J. KROMENAKER.
GRANT M. KROMENAKER.
